UNITED STATES PATENT OFFICE.

HENRY J. GILBERT, OF DAYTON, OHIO.

FLOUR-BOLT.

SPECIFICATION forming part of Letters Patent No. 371,678, dated October 18, 1887.

Application filed December 18, 1885. Serial No. 186,031. (No model.)

To all whom it may concern:

Be it known that I, HENRY J. GILBERT, a citizen of the United States, residing at Dayton, in the county of Montgomery and State of Ohio, have invented certain new and useful Improvements in Flour-Bolts, of which the following is a full, clear, and exact description, reference being had to the accompanying drawings, forming part of this specification.

10 My invention relates to that class of flour-bolts having revolving reels whose axes are slightly inclined, which reels are covered with bolting-cloth of any desired size of mesh, and into which the flour is introduced at one end 15 and the tailings delivered out at the opposite or lower end.

The object of my invention is to increase the efficiency of this class of flour-bolts by providing the reels with a series of internal self-20 adjusting oscillating buckets positively operated by mechanism at the end of the reel, and by means of which almost the entire surface of the bolting-cloth is utilized, thus facilitating the bolting of the flour.

25 The novelty of my invention will be herein set forth, and specifically pointed out in the claims.

In the accompanying drawings, Figure 1, Sheet 1, is a sectional end elevation of my improved flour-bolt, taken through the line $x-x$ of Fig. 2. Fig. 2, Sheet 2, is a sectional side elevation of the same through the line $y-y$ of Fig. 1. Fig. 3, Sheet 3, is a sectional end elevation of the reel, looking toward the tail of the same. 35 Fig. 4, Sheet 3, is an enlarged transverse section of the discharging-chute. Fig. 5, Sheet 3, is an enlarged end elevation of one of the buckets and its operating crank-arm. Fig. 6, Sheet 3, is a plan view of the same, partly in 40 section. Fig. 7, Sheet 4, is a sectional end elevation of a flour-bolt, taken through the line $z-z$ of Fig. 8, and showing my invention as applied to a double reel, the outer one of which revolves independently of the inner one and 45 at a different rate of speed. Fig. 8, Sheet 5, is a sectional side elevation of the same through the line $1-1$ of Fig. 7.

The same letters of reference are used to indicate identical parts in all the figures.

50 A is the usual bolting-chest, of any suitable construction, opening into the conveyer-boxes

B, as is usual in this class of bolts. In each end of the chest are secured hollow cylindrical boxes C and D, the former of which is provided with an upwardly-extending opening or 55 spout, a , to receive the flour, and the latter of which is provided with a downwardly-extending opening or spout, b , to discharge the tailings. The boxes C and D also serve as journals for the reel-shaft E, which may be driven by a pulley, 60 F, in the usual manner. Upon the shaft E, within the boxes C and D, are conveyer-blades $c-d$ —the former for delivering the flour into the reel and the latter for discharging the tailings through the opening or spout b .

65 The head end G of the reel has a circular opening, which fits over the inner end of the box C and comes slightly in contact with the flange e , extending circumferentially around said box. The same construction may, as illustrated, be employed for the tail end H of the reel. Both ends are supported and keyed or otherwise fastened to the shaft E by curved or bent arms I, which, if desired, may be integral with the ends.

70 The bolting-cloth J is secured to the ends G H in the usual or any suitable manner, and may be supported by any number of intermediate rings, K, carried upon spokes L, extending from hubs secured to the shaft E.

75 Within the reel at equal distances, near its circumference and extending the entire length of the same, if desired, are a series of buckets, M, preferably curved in transverse section, which buckets are supported upon spindles f, 80 journaled in one of the ends of the reel—in this instance the tail end—and upon crank-arms g, Figs. 2, 5, and 6, which crank-arms extend through and have bearing in the opposite end of the reel—in this instance the head end. The 90 outer ends of these crank-arms may be provided with friction-rollers h, as seen in Fig. 6, and are confined between two adjustable rings, i i, which may be adjusted by any suitable means, and which are attached to the inside 95 of the end of the bolting-chest, so as to form a substantially circular slot eccentric to the axis of the reel, as seen more particularly in Fig. 1. The adjustment of the parts is such that as the reel revolves in the directions of the arrow in Fig. 3 the buckets M are oscillated and take the position there shown. It will be seen

from this that the lowermost bucket at 2 has been inclined with its lower edge toward the cloth to scoop up the flour. At 3, 4, and 5 it becomes gradually more inclined, so as to hold 5 the flour close to and against the surface of the cloth. From 6 to 8 it gradually becomes horizontal to retain the flour within it and carry it beyond the top center of the reel, and from 9 to 12 it discharges the flour upon the 10 descending side of the reel, and in this way a large portion of the surface of the bolting-cloth is caused to be utilized at the same moment of time, which greatly facilitates the bolting of the flour.

15 Secured to or formed integral with the inner side of the tail end H of the reel are as many substantially radial troughs or discharging-chutes N as may be desired. The inner ends of these chutes just clear the box D, and 20 they are so arranged that they gather up the tailings and empty them into the box D, which, unlike the box C, has an inner end wall, j, as seen in Figs. 2 and 3, and an open top or mouth to receive the tailings, which are then 25 discharged by the conveyer-blade d out through the opening b.

In Figs. 7 and 8 my invention is shown applied to a double reel, which, in addition to the construction above described, has two rings, 30 O P, fitted but free to turn independently upon the ends G H. These rings are connected by the tie-rods k, thus constituting a frame-work, around which the outer bolting-cloth, R, is stretched, and to which it is secured in any suitable manner. The former of these rings, O, 35 has upon its outer side a gear-ring, S, with which meshes a pinion, T, upon a shaft, U, secured in any suitable journal, V, the outer end of which shaft is provided with a pulley, W, 40 from which a belt, Y, extends and passes over a pulley, l, keyed upon the shaft E. In this manner the outer reel is driven at a lower rate of speed than the inner one, and by twisting the belt Y a reverse motion may be given to it, if desired. It will be observed that in this 45 construction the cam-guides i and crank-arms g are applied at the tail end of the reel.

Where a single reel is used, a belt extends from the pulley l to and around pulleys m upon 50 the ends of the conveyer-shafts in the box B.

Where, as in Figs. 7 and 8, the double reel is employed, a belt, n, may extend from a pulley, o, upon the shaft U, down and around the conveyer-pulleys m.

55 To aid in supporting the rings O P and preventing friction with the ends G H, I employ friction-rollers p, which journal in the frame-work on each side, bearing against and under the outer side of the rings O P, and serve to 60 support the same.

Having thus fully described my invention, I claim—

1. In a flour-bolt, the combination, with the bolting-reel, of a series of internal oscillating buckets hung therein, projections on the end 65 of the buckets, and a cam at the end of the bolt, with which the projections at all times engage to cause the positive oscillation of the buckets and positively control their position at all times, substantially as described. 70

2. The combination, with a bolting-reel, of a series of buckets journaled therein and provided at one end with crank-arms, and a cam, with which said crank-arms are at all times engaged, so arranged as to cause the positive 75 oscillation of the buckets and at all times positively control their position, substantially as described.

3. In a flour-bolt, the combination, with the reel, of the series of oscillating buckets therein, 80 each provided with a projection, and a circular cam-groove at one end of the bolt, with which said projections engage, arranged eccentric to the axis of the reel, whereby the position of the buckets is at all times positively 85 regulated and controlled, substantially as described.

4. In a flour-bolt, the combination, with the reel, of the series of oscillating buckets therein, 90 each provided with a projection, and a cam-groove, with which said projections co-operate, and which regulates and controls their position at all times, so arranged with reference to the direction of rotation of the reel as to cause the buckets to carry up the material and 95 gradually pour it on the descending side of the reel, substantially as described.

5. The combination of a bolting-reel, a series of pivoted elevator-buckets therein, which carry chop to the upper portion of the reel, 100 and a cam for controlling the position of the said buckets at all times, so arranged as to discharge their contents upon the cloth upon the descending side of the reel, substantially as described. 105

6. The combination of an inner reel, self-adjusting oscillating buckets therein, rings fitted and free to revolve upon the ends of the inner reel, one ring being formed with internal gear-teeth, tie-rods connecting the rings, an outer bolting-cloth attached to the rings, a pinion meshing with the gear-teeth and driven from the inner reel, and rollers supporting the ring at each side of the pinion, substantially as and for the purpose described. 110

HENRY J. GILBERT.
